UNITED STATES PATENT OFFICE.

WILLIAM E. SHREFFLER, OF MULBERRY, INDIANA.

ACETYLENE-GAS GENERATOR.

No. 909,698.

Specification of Letters Patent.

Patented Jan. 12, 1909.

Application filed July 2, 1908. Serial No. 441,626.

To all whom it may concern:

Be it known that I, WILLIAM E. SHREFFLER, a citizen of the United States, residing at Mulberry, in the county of Clinton and 5 State of Indiana, have invented certain new and useful Improvements in Acetylene-Gas Generators, of which the following is a specification.

10 My invention relates to improvements in gas-generators, or more particularly to that class of devices employed for the generation and storage of acetylene gas by the decomposition of calcium carbid.

15 The object contemplated by this invention is the provision of means for automatically generating and storing gas in a facile and economical manner.

20 To this accomplishment of the recited object and others coördinate therewith the preferred embodiment of the invention resides in that construction and arrangement of parts, hereinafter described, illustrated in the accompanying drawings, and embraced within the scope of the appended claims.

25 In said drawings:—Figure I is a longitudinal sectional view of the complete apparatus, and Fig. II is a transverse sectional view thereof.

30 Similar reference characters indicate corresponding parts throughout the several views.

Primarily, my invention embraces a co-operative generator and a gasometer or storage tank. The generator comprises in its 35 construction a tank 1, and a bell 2, the latter being provided with pairs of guide rollers 3 and being vertically movable on the standards 4, which are fixedly secured in any convenient way adjacent the bottom of the 40 tank 1. Arranged centrally of the bell 2 and projecting to either side of the top thereof is the inclosure 5 of any desired cross sectional contour. This inclosure is designed to accommodate a basket or other 45 suitable carbid containing device 6, the same to be connected to the lower terminal of the depending rod 7, which is screw threaded at points 8 and 9 for consecutive engagement with the complementary screw 50 threaded portion of the removable cover 10 of the said inclosure 5, these parts being readily disassembled when occasion requires the removal of the basket and the substitution therein of fresh carbid. To control the 55 intermittent subjection of the carbid to the water contained in tank 1, which in an ob-

vious manner defines a seal, I prefer to employ certain means which will accomplish this result without any appreciable loss. To this end I utilize at the lower terminal of 60 the inclosure 5 a hinged door 11 projecting slightly beyond one side of the said inclosure and having suitably attached at this point a depending weight 12 which insures the maintenance of a closed position of the door 65 relative to the inclosure. However, as the bell 2 gravitates the weight 12 will contact with the bottom of the tank 1, thereby releasing the weight from the extended terminal of the door 11 and permitting the latter to open and in this way subject the carbid in the basket to the decomposing action of the water. Communication between the bell 2 and the inclosure 5 is established by any suitable by-way connection such, for 70 example, as 13, and the said cover carries a vertically extending dome 14, the function of which will be hereinafter set forth.

The gasometer is constituted by a tank 15 and bell 16, the latter carrying guide 80 rollers 17 which work on the vertically extending standards 18. Generally speaking, the relations assumed by the bell and the tank are relatively the same as the arrangement of the corresponding component portions of the generator, and a seal is likewise formed. The generator and the gasometer are connected by a suitable induction pipe 19 the terminal portions thereof being vertically disposed within the bell of the generator and gasometer respectively and are in alinement or registration with the dome 14, and dome 20. The service pipe 21 occupies a similar position with respect to the dome 20 of the bell 16. At any suitable 85 point along the horizontal extent of the induction pipe 19 I incorporate a gate valve 22, of any preferred type. Having one distal end connected to the gate valve 22 and its other proximal end attached to a chain 100 or rope 23, as at 24, is the vertically disposed rod 25, the upper distal end thereof being provided with a plurality of apertures 26, through the medium of which I may attain the desired adjustment of the longitudinally 105 arranged rod 27, the latter being hingedly connected to the upright 28, secured to the tank 1 of the generator, at 29, and projecting from this point of connection so as to be in line for engagement with the bell 2, 110 in a manner which will be presently explained. To facilitate the movement of the

chain 23 I have provided a pulley 30 which is loosely mounted on the outer terminal of the laterally extending bar 31 of the bell 16.

With the foregoing explication the operation of the apparatus will now be described, it being assumed that the maximum quantity of gas is contained in the bell 16 of the gasometer. As the gas is being consumed the volume in the gasometer decreases and the bell 16 descends until sufficient pull is exerted by the weight 32, thus forcing the rod 25 downwardly and at the same time imparting thereto a slight oscillation. By this method the gate valve 22 is opened and the gas is permitted to make its exit from the generator to the gasometer, the said gate valve remaining open until the gasometer is replenished. Just previous to the maximum ascent of the bell the weight is released and the gate valve closed. It follows that when the gas is liberated from the gasometer the volume in the generating tank decreases proportionately, whereupon the bell 2 descends until the door 11 of the inclosure 5 is opened, as hereinbefore explained, thereby permitting the calcium carbid held in the basket 6 to be completely saturated with water, and consequently the generation of acetylene gas. As the generation of gas continues the inverted cover ascends until the basket is raised out of the water, the door of the inclosure being closed, and the production of gas ceasing. This simple but effective process of generating gas by means of intermittently and automatically controlling the movement of the carbid basket with relation to the water is continued through the above steps as more gas is required. If at any time it is desired to remove the decomposed contents of the basket it is only necessary to unscrew the rod 7 and raise the same until the screw threads 9, thereof, are placed in communication with the complementary screw threads 8 of the cover 10, the latter being detached in any suitable way from the inclosure 5.

In practice I find it impossible to prevent altogether the formation of gas from calcium carbid, even for some time subsequent to the expulsion of the water, this material, in a sense, being deliquescent or having a strong affinity for moisture, and in order to preclude accident due to an accumulation of the gas under pressure, I have designed the rod (27), which is in operative relation to the gate valve (22), as a safety release expedient the terminal portion thereof being adapted to be engaged by the top of the bell (2). Should the generation of the gas be prolonged sufficiently, the surplus gas thus evolved will force the bell (2) into engagement with the terminal of the rod (27) and push the rod (25) downwardly, thus opening the gate valve (22) and permitting said gas to pass through pipe (19) into the bell (16),

and be stored therein unless this after generation is sufficient to raise the bell (16) so as to expose the aperture (33), when the gas will escape.

In both the generator and the gasometer I prefer to employ domes 14 and 20 which insures the production of an excellent quality of acetylene gas.

Previous to passing the gas from the gasometer the same is subjected to any suitable filtering process, a conventional form of cotton filter being indicated by 36 in the drawings. I also prefer to connect the service pipe 21 and the pipe 35 with a by-way 37. The agitator 38 used in conjunction with the generator is also of obvious utility.

By subjecting the carbid to the treatment as previously set forth a certain decomposition or scaling off of the exterior of the carbid takes place, the different stages of the dipping process and thus all available use of the carbid is accomplished. Furthermore, it will be observed that I have produced a simple, effective, and entirely automatic gas generating and storing apparatus.

It should be understood that in its broader aspects my invention comprehends the employment not only of the various means described, but of equivalent means for performing the recited functions. While the arrangement shown is thought, at the present time, to be preferable, I desire to reserve the right to effect such modifications and variations thereof as may come within the scope of the appended claims.

Having thus described the invention, what is claimed, is:

1. In an apparatus of the class described, the combination with a generator and a gasometer of means common to and adapted to be actuated by said generator and gasometer for sequentially controlling the production of gas in and the liberation of surplus gas from the generator, and the supply of gas to the gasometer.

2. In an apparatus of the class described, the combination with a generator and a gasometer of a gate valve, and means associated therewith and adapted to be automatically actuated by said generator and gasometer for sequentially controlling the production of gas in and the liberation of surplus gas from the generator, and the supply of gas to the gasometer.

3. In an apparatus of the class described, the combination of a generator-tank and a gasometer-tank, a bell in each, and means common to and adapted to be actuated by said bells for sequentially controlling the production of gas in and the liberation of surplus gas from the generator, and the supply of gas to the gasometer.

4. In an apparatus of the class described, the combination of a generator-tank and a gasometer-tank, a bell in each, and means

adapted to be automatically actuated by said generator and gasometer for sequentially controlling the production of gas in and the liberation of surplus gas from the generator, 5 and the supply of gas to the gasometer.

5. In an apparatus of the class described, the combination of a generator-tank and a gasometer-tank, a bell in each, and means common to and adapted to be automatically 10 actuated by said generator and gasometer for sequentially controlling the production of gas in and the liberation of surplus gas from the generator, and the supply of gas to the gasometer.

15. 6. In an apparatus of the class described, the combination with a generator-tank and a gasometer-tank, a bell in each, and adjustable means adapted to be actuated by said bells for sequentially controlling the production 20 of gas in and the liberation of surplus gas from the generator, and the supply of gas to the gasometer.

7. In an apparatus of the class described, the combination with a generator-tank and 25 a gasometer-tank, a bell in each, a gate valve, and means associated with said valve and adapted to be actuated by said bells for sequentially controlling the production of gas in and the liberation of surplus gas from 30 the generator, and the supply of gas to the gasometer.

8. In an apparatus of the class described,

the combination with a generator-tank and a gasometer-tank, a bell in each, a gate valve, and adjustably connected levers associated 35 with said valve and adapted to be actuated by said bells for sequentially controlling the production of gas in and the liberation of surplus gas from the generator, and the supply of gas to the gasometer.

9. In an apparatus of the class described, the combination with a generator and a gasometer and a communicating connection therefor, of a gate valve mounted on said connection, a vertically disposed rod connected to said gate valve, a pulley mounted on said gasometer, a weighted chain passing over said pulley and connected to the proximal end of said rod, a horizontally extending member adjustably connected to the distal end, said rod having its other terminal end, said rod having its other terminal hingedly connected and projecting in line for engagement with the movable part of the generator, these connections serving to 55 control the production and admission of gas to the gasometer and as a safety release device.

In testimony whereof I hereunto affix my signature in presence of two witnesses.

WILLIAM E. SHREFFLER.
